(57) **CLAIM**

The ornamental design for a pillow book, as shown.

DESCRIPTION

FIG. 1 is a perspective view of a first embodiment of a pillow book, in an open condition showing exposed pages of embodiment 1.

FIG. 2 is a front view of a pillow book, in a closed condition, according to one embodiment of this invention;

FIG. 3 is a rear view of the pillow book, as shown in FIG. 2;

FIG. 4 is a side view of the pillow book, as shown in FIG. 2;

FIG. 5 is a side view, opposite the side view shown in FIG. 4, of the pillow book, as shown in FIG. 2;

FIG. 6 is a top view of the pillow book, as shown in FIG. 2;

FIG. 7 is a bottom view of the pillow book, as shown in FIG. 2;

FIG. 8 is a perspective view of the pillow book in the closed condition, as shown in FIGS. 2–7;

FIG. 9 is a perspective view of a second embodiment of a pillow book, in an open condition showing exposed pages of embodiment 2.

FIG. 10 is a front view of a pillow book, in a closed condition, according to another embodiment of this invention;

FIG. 11 is a rear view of the pillow book, as shown in FIG. 10;

FIG. 12 is a top view of the pillow book, as shown in FIG. 10;

FIG. 13 is a bottom view of the pillow book, as shown in FIG. 10;

FIG. 14 is a side view of the pillow book, as shown in FIG. 10;

FIG. 15 is a side view, opposite the side view shown in FIG. 14, of the pillow book, as shown in FIG. 10; and,

FIG. 16 is a perspective view of the pillow book in the closed condition, as shown in FIGS. 10–15.

The dashed lines indicate areas to display graphics and form no part of the claimed design.
